UNITED STATES PATENT OFFICE.

JACOB R. FRY, JR., OF SPRINGFIELD, OHIO.

CRANK-COUPING.

SPECIFICATION forming part of Letters Patent No. 290,565, dated December 18, 1883.

Application filed October 24, 1883. (No model.)

To all whom it may concern:

Be it known that I, JACOB R. FRY, Jr., a citizen of the United States, resident at Springfield, in the county of Clarke and State of Ohio, have invented certain new and useful Improvements in Crank-Couplings; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of a side elevation of the crank-coupling; Fig. 2, detail view.

This invention has relation to crank-couplings; and it consists in the construction and novel arrangement of devices, as will be hereinafter fully described, and particularly pointed out in the claim appended.

Referring by letter to the accompanying drawings, *a* designates the coupling-sleeve, having a series of tenons, *b*, on its ends, arranged radially, their peripheral faces being in line with the periphery of the sleeve itself, as shown.

d and *e* represent eyes, having radially arranged near the peripheries of said eyes recesses or seats *f*, for the reception of tenons *b* on the sleeve *a*. A bolt, *g*, is passed through the eyes *d* or *e*, engaging the sleeve *a*, and is secured in place by a nut, *h*, so that the parts of the crank, which is a double or a triple crank, are separably connected, and when any

portion of it becomes broken its place may be easily and quickly supplied by a similar unbroken portion. All of the crank-bends are coupled in this way, and any number of bends that are practicable may be coupled in this way between the crank-journals. By employing this coupling the crank-bends may be aligned or set at the proper angles.

The facility with which a broken portion can be replaced and the ease with which an adjustment of the crank-bends can be made render the coupling a cheap and desirable one in all places where compound cranks are needed.

The couplings or connections are further secured by rivets or bolts passed through the interlocked sections; but this feature is not an essential one.

Having thus fully described my invention, what I claim as new and useful, and desire to secure by Letters Patent, is—

In a crank-coupling, the combination, with the coupling-sleeve having radially-arranged tenons on its ends, of the arms of the crank-bends, provided with eyes having radially-arranged recesses or seats on their inner faces, and the bolt and securing-nut for holding them in place together, substantially as specified.

In testimony whereof I affix my signature in presence of two witnesses.

JACOB R. FRY, JR.
